CLAIM

The ornamental design for carafe handle and lid, as shown and described.

DESCRIPTION

FIG. 1 is a perspective view as seen from the top, front, and left side of a carafe handle and lid showing our new design; FIG. 2 is a top plan view thereof;

FIG. 3 is a right side elevational view thereof, the left side elevational view being a mirror image of the right side elevational view;

FIG. 4 is a front elevational view thereof; and,

FIG. 5 is a rear elevational view thereof.

The broken lines in FIG. 1 showing the carafe body and handle support are used for illustrative purposes only and form no part of the claimed design.

The broken lines in FIG. 5 showing the portion of the handle located adjacent the carafe body are used for illustrative purposes only and forms no part of the claimed design because this surface of the handle is not shown during normal use.
